UNITED STATES PATENT OFFICE.

FREDERICK MARSHALL, OF PITTSBURGH, PENNSYLVANIA.

GAME APPARATUS.

Application filed March 25, 1926. Serial No. 97,428.

In general, my invention relates to mechanical means for throwing dice or similar objects.

More particularly my invention comprises 5 a dice-cup mounted to rotate on a vertical axis and provided with spring means to return it to a predetermined position of rest, and an actuating member also movable on a vertical axis and arranged to cause the 10 dice-cup to rotate with it to a predetermined degree against the influence of the spring means, whereupon the operative connection between the actuating member and the dice-cup is automatically released and the dice-cup 15 is precipitously rotated by its spring return in the opposite direction into its position of rest.

The actuating member is preferably a disk arranged for hand-rotation.

20 I preferably provide a second member or disk moving with the actuating member and the dice-cup, the mechanism being so arranged that when said second member attains a predetermined position the release 25 and return of the dice-cup takes place.

The second member is preferably a disk having marked on its face one or more numbers or other symbols and when a chosen symbol attains a given position the release 30 of the dice-cup occurs.

In the preferred embodiment of my invention the mechanism is inclosed in a case having a lid provided with transparent portions to expose to view the dice-cup and the said second member, the actuating member protruding laterally from the case so as 35 to be rotated by a finger of the player.

Means are provided for preventing the rotation of the actuating disk in the wrong 40 direction.

Other novel features of construction, and also of arrangement of parts will appear from the following description.

In the accompanying drawings, wherein 45 I have illustrated the best embodiment of the principles of my invention now known to me, Fig. 1 is a plan view; Fig. 2 is a similar view with the lid of the case removed; Fig. 3 is a vertical section taken 50 along the line III—III in Fig. 1; Fig. 4 is a side elevation of the disks and the dice cup, and Fig. 5 is an inverted plan view of the dice cup.

Referring to the drawings 1 represents the 55 flat shallow box or casing having a removable lid 2. 3 represents a flat shallow dice-

cup having an axial hub 4 which raises the cup slightly above the floor of the casing, and 5 is a pivot-screw extending through said hub and screwed into a threaded hole 60 in the floor of the casing.

The hub 4 is provided with a perimetral notch 6 which is engaged by one end of a spring 1 whose other end is secured to the stud 8 extending upwardly from the floor 65 of the box. 9 represents an abutment pin against which the spring 7 bears as the cup is rotated counterclockwise.

10 represents a disk which is concentrically connected to the smaller disk 11 by 70 means of their common hub 12 and said disks are mounted to rotate on the pivot screw 13 which extends through said hub and is screwed into a threaded hole in the bottom of the case 1. The perimetral edge 75 of the disk 10 protrudes through a slot 14 in the end wall of the case 1 so that it may be rotated by the finger of the player. The perimetral edge of the disk 10 is preferably milled so that it may be easily rotated with 80 a finger.

The disk 11 has its upper face marked or provided with one or more numerals or other symbols. The lid 2 has two transparent or glass-filled portions 15 and 16, 85 the latter being shown heart-shaped. The portion 15 exposes the dice box to view. The portion 16 exposes a portion of the disk 11 to view, the aperture in the solid portion of the disk surrounding the transparent portion 16 being preferably provided with a projection or pointer 17 in relation to which the player reads the symbol or symbols on the disk 11.

Means are provided whereby the disks 10 95 and 11 may be rotated in but one direction; clockwise in Figs. 1 and 2. Thus a leaf spring 18 attached to the side wall of the case has a bent free end which engages suitable teeth on the perimeter of the disk 11. 100

The disk 10 is provided on its upper face with a post 19 which picks up a lever 20 fixed to the dice-cup and extending radially into the path of said post.

Thus as the disk 10 is rotated clockwise, 105 the post 19 picks up the lever 20, as shown in solid lines in Fig. 2, and rotates the dice-cup 3 counterclockwise until the post moves off the end of the lever, as shown in dotted lines in Fig. 2; whereupon the spring 7, 110 which has been storing power during the counterclockwise rotation of the dice-cup,

causes the dice-cup to be rotated violently back to its position of rest, thus throwing the dice 21 which are contained in the cup.

In case the dice-cup be not held truly horizontal, there would be a tendency for the dice to slide along the lower side of the cup without upsetting. To prevent this, I corrugate the perimetral wall of the cup, so that such sliding is prevented and the dice 10 are given repeated kicks during the throwing movement of the dice-cup. To further facilitate the upsetting or proper throwing of the dice, I provide the bottom of the cup with a plurality of raised ribs 22 which may 15 be radially disposed, and which may be formed by pressing up the material of the cup. When the dice-cup is thrown these ribs aid materially in producing a proper throw of the dice.

20 My invention provides a convenient and attractive game apparatus which may be entertainingly used in playing a great number of games.

It will be noted that the indicating disk 25 11 is provided with an annular series of graduations, and with certain of the same marked with numerals. Thus in the drawings the numerals "0," "5," "10," "15" and "20" are placed opposite the corresponding 30 graduations.

The lever 20 on the dice cup 3 and the post 19 on the disk 10 are arranged so that when a selected graduation moves into position at the pointer 17 the dice cup is released 35 and the dice are thrown. Thus in the apparatus illustrated in the drawings the twenty-first graduation on the small disk 13 is the selected graduation whose registration with the pointer 17 is simultaneous with the 40 release of the dice cup.

One manner of employing the above described game apparatus is for a plurality of players to take turns in rotating the disk 10 to bring a graduation chosen by the individual player into registration with the pointer 17, each player being required to rotate the disk 10 sufficiently to advance at least one graduation on the disk 13 but not more than say six graduations for one play, 45 so that a player can not be sure of shooting the dice every time he plays. The aim of the player is to make such turns of the disk so as to control the shooting of the dice, and either have it occur during one of his turns 50 or to make it occur during the turn of an opponent, according to the manner of scoring. The player's aim is to cause the dice to be thrown when it will score in his favor.

60 Thus the rules may provide for a score in a player's favor first when the dice are thrown during one of his turns of play, and next when the dice are thrown during an opponent's turn of play. Thus the game in a degree resembles chess, in that the plays are 65 planned ahead so as to effect a throw dur-

ing one of the player's turn and to prevent a throw during the turn of an opponent or vice versa, as the rules may provide.

Thus, at the beginning of the game, assuming that the zero graduation is in registration with the pointer, the first player must move the disk any number of graduations not exceeding six. Suppose the first player moves the disk the full six graduations and then his opponent moves another 70 six graduations. If the first player then moves another six graduations his opponent can throw the dice by moving the disk three more graduations. Suppose however the first player on his second play moves the 75 disk but two graduations. Then the opponent can not throw the dice on his second play because he is not permitted to move the disk more than six graduations which would bring the twentieth graduation into 80 registration with the pointer. However, the first player on his third play by moving the disk one graduation, bringing the twenty-first graduation into registration with the 85 pointer is able to shoot the dice. If the rules provide that on the second series of play the first player can score only if his opponent shoots the dice, it is evident that the first player, by planning ahead and selecting the number of graduations which he moves 90 the disk on each play, can force his opponent to shoot the dice and thus obtain a score in his own favor.

Thus skill is involved first in choosing the proper graduations or combination of 100 graduations which will cause the dice to be thrown when a throw will score for the player in question, and second to choose the proper graduations or combination of graduations to avoid making a throw of the dice 105 when such a throw would score against the player.

What I desire to claim is:—

1. In a game apparatus, the combination of a dice-cup mounted to rotate, an actuating member mounted to turn on an axis parallel with the axis of the dice-cup, an intermittent pick-up connection whereby the turning actuating member causes the dice-cup to be rotated from its position of rest, and stored power means for precipitously returning the dice-cup to its position of rest. 110

2. In a game apparatus, the combination of a dice-cup mounted to rotate, a member mounted to rotate on a parallel axis and adapted to be actuated by the player, a post on said member and a radially disposed lever on said dice-cup comprising a pick-up connection between the member and the dice-cup, and stored power means for precipitously rotating the dice-cup back into its position of rest when said pick-up connection becomes released. 120

3. In a game apparatus, the combination of a dice-cup mounted to rotate, a member 130

- mounted to rotate on a parallel axis and adapted to be actuated by the player, a post on said member and a radially disposed lever on said dice-cup comprising a pick-up connection between the member and the dice-cup, stored power means for precipitously rotating the dice-cup back into its position of rest when said pick-up connection becomes released, and indicating means moving with said member and arranged to produce a given indication contemporaneously with the release of the pick-up connection.
4. In a game apparatus, the combination of a dice-cup mounted to rotate, a member mounted to rotate on a parallel axis, a pick-up connection between said dice-cup and said member comprised of a post carried by one of the same and a radially disposed lever carried by the other of the same whereby the rotation of the member will cause a partial rotation of the dice-cup, and stored power means for precipitously returning the dice-cup to its position of rest when the pick-up connection is released.
5. In a game apparatus, the combination of a dice-cup mounted to rotate, a member mounted to rotate on a parallel axis, a pick-up connection between said dice cup and said member comprised of a post carried by one of the same and a radially disposed lever carried by the other of the same whereby the rotation of the member will cause a partial rotation of the dice-cup, stored power means for precipitously returning the dice-cup to its position of rest when the pick-up connection is released, and indicating means moving with the member arranged to present a given indication when the pick-up connection is released.
6. In a game apparatus, the combination of a dice-cup mounted to rotate, a disk mounted to rotate on a parallel axis, a second disk concentric with the first mentioned disk and provided with an indicating symbol, a pick-up connection between the first mentioned disk and the dice-cup whereby the rotation of the first mentioned disk causes a partial rotation of the dice-cup, and stored power means whereby when the pick-up connection is released the dice-cup is precipitously returned to its position of rest, the second named disk being arranged to display its symbol in an indicating position at the instant of such release.
7. In a game apparatus, the combination of a dice-cup mounted to rotate, a disk mounted to rotate on a parallel axis, a second disk concentric with the first mentioned disk and provided with an indicating symbol, a pick-up connection between the member and the dice-cup, stored power means for precipitously rotating the dice-cup back into its position of rest when said pick-up connection becomes released, and indicating means moving with said member and arranged to produce a given indication contemporaneously with the release of the pick-up connection.
8. In a game apparatus, the combination of a dice-cup mounted for rotation, means for causing a rotary motion of said dice-cup, and stored power means for precipitously returning the dice-cup to its position of rest, the perimetral wall of said dice-cup being provided with inwardly extending projections adapted to impinge against the dice and augment the throwing effect of the return movement of the dice-cup.
9. In a game apparatus, the combination of a dice-cup mounted for rotation, means for causing a rotary motion of said dice-cup, and stored power means for precipitously returning the dice-cup to its position of rest, the perimetral wall of said dice-cup being corrugated to augment the throwing effect of the return movement of the dice-cup.
10. In a game apparatus, the combination of a dice-cup mounted for rotation, means for causing a rotary motion of said dice-cup, and stored power means for precipitously returning the dice-cup to its position of rest, the dice-cup being provided with projections on its perimetral wall and ribs on its floor to augment the throwing effect of the return movement of the dice-cup.
11. In a game apparatus, the combination of a dice-cup mounted for rotation, means for causing a rotary motion of said dice-cup and stored power means for precipitously returning the dice-cup to its position of rest, the dice-cup being provided with a corrugated perimetral wall and radially disposed ribs on its floor to augment the throwing effect of the return movement of the dice-cup.

Signed at Pittsburgh, Pa., this twentieth day of March, 1926.

FREDERICK MARSHALL.
